Des. 205,891
Patented Oct. 4, 1966

205,891

METAL GRATING

Mauro A. Feliziani, Plainview, N.Y., assignor to Hope-
man Brothers, Inc., New York, N.Y., a corporation of
Delaware

Filed Apr. 29, 1965, Ser. No. 85,023

Term of patent 14 years

(Cl. D13—1)

FIG. 1.

FIG. 4.

FIG. 5.

FIG. 6.

FIG. 7.

FIG. 8.

FIG. 2.

FIG. 3.

FIGURE 1 is a top perspective view of the metal grating showing my new design;

FIGURE 2 is a top plan view thereof;

FIGURE 3 is a bottom plan view thereof;

FIGURE 4 is a front elevation thereof;

FIGURE 5 is a rear elevation thereof;

FIGURE 6 is a right-hand elevation thereof;

FIGURE 7 is a left-hand elevation thereof; and

FIGURE 8 is an enlarged fragmentary view of the top thereof.

I claim:

The ornamental design for a metal grating, as shown.
